LIGHT DETECTORS

Charles Franklin Hendee, Irvington, N.Y., assignor, by
mesne assignments, to North American Philips Com-
pany, Inc., New York, N.Y., a corporation of Dela-
ware

Filed Dec. 23, 1953, Ser. No. 399,870
7 Claims. (Cl. 250—207)

This invention relates to a method of and apparatus for detecting light radiation and more particularly to improved photomultiplier tube circuits for determining the intensity of an incident flash of light which has an intensity far below the light level detectable by normal direct voltage operation of photomultiplier tubes.

The conventional photomultiplier tube is a high vacuum device in which the photo-current produced at a light-sensitive cathode is multiplied many times by secondary emission occurring at successive intermediate electrodes or dynodes prior to reaching the collector or anode of the tube. For normal operation of a photomultiplier tube, a rated operative value of constant direct voltage is impressed on the successive tube electrodes to direct electron flow in a direction from the light-sensitive cathode to the anode via each of the dynodes. The resultant output current is a linear function of the incident illumination on the cathode.

However, photomultiplier tubes are notoriously noisy and the noise is particularly undesirable when the tubes are used to detect low light levels. A recognized source of such noise is the thermal emission of electrons from the photocathode and dynodes of the tube. Thermal emission of electrons is a sporadic emission of electrons from the tube electrodes which occurs at room temperature but which may increase or decrease depending upon the increase or decrease, respectively, of the electrode temperature. Ordinarily when the tubes are used at very low light levels, it is customary to cool them, for example, with Dry Ice, to low temperatures in order to reduce the noise caused by the thermal electrons and thereby to enhance the precision of measurement by a more favorable signal-to-noise ratio. But such cooling is relatively inexpensive and cumbersome and, in many cases, inconvenient.

In many circuits which utilize the output from photomultiplier tubes, operating signals stronger than those yielded at the output of a conventional direct-voltage operated photomultiplier tube are required. The desired signal strength may sometimes be obtained by feeding the output of the photomultiplier tube to an amplifying circuit or, more conveniently, by merely increasing the value of the direct voltage at the tube electrodes. However, when the value of the direct voltage at the electrodes is elevated beyond the rated value, gas-generated noise is likely to occur in the tube. This noise is introduced as a result of excessive bombardment of the dynodes and anode by high velocity electrons which release positive particles, or ions, from the bombarded electrodes. These ions flow toward the photocathode and strike intermediate dynodes which release electrons therefrom to produce an unwanted signal in the output of the tube. The production of gas-generated noise is usually the limiting factor with respect to the degree of gain which can be realized from conventional photomultiplier tube circuits employing a direct voltage on the tube electrodes.

Circuits employing a photomultiplier tube have been used to analyze the intensity of a flash of light as a function of time. This may be accomplished by observing the output of a photo-tube or photomultiplier on the screen of an oscilloscope, if sufficient gain is provided between the photo-emitting surface and the oscilloscope and, if in addition, the light intensity at the photo-emit-

2

ting surface is great enough to provide a relatively large number of photo-electrons during any interval of the flash. If either of these two conditions is not met, this method is not feasible.

When the intensity of a light flash is low, a photomultiplier tube operating at its rated direct voltage may not be able to determine the intensity or even the presence of the light due to the masking effect of the thermal noise in the tube.

The principal object of the invention is to provide a method and apparatus to determine not only whether a weak light flash is present but, when it is present, also to determine its intensity and, furthermore, to determine how its intensity varies with time. Moreover, this invention seeks to provide means by which it is possible to determine the intensity of repetitive light flashes even where the intensity is so low that, for example, only one photo-electron is emitted for every 100 flashes.

It is also an object of this invention to provide apparatus for the detection of light which because of its low intensity has been heretofore undetectable.

It is a further object of this invention to provide an improved photomultiplier tube circuit wherein the photomultiplier tube is operated at voltages many times the rated direct voltage without producing gas-generated noise therein.

It is another object of this invention to provide high gain, e.g., of the order of 1000 times higher than with normal direct voltage operation, in a photomultiplier tube for a short duration of time.

It is still another object of this invention to observe the light intensity change during any particular time interval of a weak flash of light.

Yet another object of the invention is to provide a light pulse-code communication system.

A further object of the invention is to provide a light pulse-object detection system.

It is still another object of the invention to provide a light pulse friend or foe detection system.

40 Briefly stated, in a circuit according to the invention, the electrodes of the photomultiplier tube are normally cut-off from all operating voltage, thereby rendering the tube normally inoperative, and only during a short interval of time corresponding to the interval in which the 45 incoming light intensity is to be observed, are voltages, which may be several times greater than the rated direct voltage of the tube, impressed on the electrodes. By restricting the interval of time during which the photomultiplier tube is on, to one of sufficiently short duration, e.g., one micro-second or less, gas-generated noise 50 current is unable to develop. This effect is obtained even at operating voltages many times greater than the rated direct voltage such that gain is appreciably stepped up while noise is maintained at substantially zero level. The 55 mass of the positive ions is much greater than that of the electrons. Therefore, during the interval in which the voltage is on the tube, these positive ions do not complete one transit between the dynodes and, consequently, cannot generate secondary electrons.

60 The output of the photomultiplier tube is applied to an integrating circuit and then it may be indicated, for example, by means of an electronic micro-ammeter. Consequently, with this pulsing technique considerably higher gains for a short duration of time are obtained in photomultiplier tubes and very few thermal electrons are received in the integrating circuit. The thermal noise in the tube is reduced by a factor equal to the ratio of the time the voltage is on to the time it is off.

65 In accordance with another aspect of this invention, the 70 intensity of a light pulse, or any part thereof, as a function of time, is determined by observing the output of a photomultiplier tube pulsed in accordance with this in-

vention as the tube pulsing operation is displaced in phase throughout the interval of the light pulse, or the desired part thereof.

Still further objects and advantages of the invention will be apparent from the following description and appended claims considered together with the accompanying drawing, in which:

FIG. 1 is a schematic diagram of a simplified embodiment of a pulsed photomultiplier tube circuit in accordance with the invention;

FIG. 2 illustrates one form of a pulse generator which may be used in the circuit in accordance with the invention;

FIG. 3 is a more detailed diagram of another embodiment of a pulsed photomultiplier tube circuit in accordance with the invention;

FIG. 4 illustrates a light-beam communication system in accordance with this invention;

FIG. 5 illustrates a light-beam ranging system in accordance with this invention; and

FIG. 6 illustrates a light-beam identification and/or signaling system.

Referring to the drawings and more particularly to FIG. 1, in an arrangement according to the invention there is provided a light source 10, for example, a light emitting hydrogen thyratron which may be controlled to produce light pulses at a predetermined rate. Means to activate the light source, such as a variable trigger rate generator 11 (e.g., an astable multivibrator), is coupled to the light source 10 through conductor 12 to control the recurrence rate of the light pulses. In this manner, which is known in the art, a light flash having a duration of less than 1 microsecond may be produced.

The light-sensitive cathode 13a of a photomultiplier tube 13 is disposed to receive light from the light source 10. The photomultiplier tube 13, illustrated in FIG. 1, has nine dynodes, each designated by reference character 13b, disposed between the cathode 13a and an anode 13c and it will be readily apparent that other types of photomultiplier tubes may be substituted. A voltage divider 14 having a plurality of similar resistors 15, each having a low value of the order of, for example, 100 ohms, is connected between the cathode 13a and a point of ground potential with intermediate connections or taps thereof connected to the dynodes 13b.

A pulse generator 16, which produces photomultiplier tube operating pulses, is connected to the cathode 13a of the photomultiplier tube 13 through a coupling capacitor 17 and, furthermore, to the dynodes 13b through equally spaced taps on the voltage divider 14. The pulse generator 16 is preferably provided with means for controlling the pulse amplitude and the pulse width.

The output voltage from the trigger rate generator 11, in addition to being applied to the light source 10, is also applied as a synchronizing impulse to the pulse generator 16 through a variable delay device 18 which provides means for attaining coincidence between the incoming light pulses from light source 10 and the tube operating pulses from pulse generator 16 in photomultiplier tube 13.

The output circuit of the photomultiplier tube 13 is comprised of an integrating circuit 22, illustrated by the resistor 19 and the capacitor 20, and an indicating device 21 connected through the integrating circuit 22 to the anode of the tube 13. The indicating device 21 may be constituted, for example, by an electronic micro-ammeter or a recording potentiometer whenever a permanent record of the output signal is desired.

In the operation of the circuit illustrated in FIG. 1, it will be seen that a light flash from light source 10 is emitted, under the control of the trigger rate generator 11, and intercepted by the light-sensitive cathode of the photomultiplier tube 13. The rate of the voltage pulses from the pulse generator 16 is preferably equal to the rate of the light pulses from the light source 10. This

rate is not critical and may be, for example, at a rate within the range from about 1 to 100,000 pulses per second.

During the time when the light flash is received at the cathode of photomultiplier tube 13, a voltage pulse having an amplitude which may be many times the normal direct voltage operating value of the photomultiplier tube 13 is applied to the electrodes of tube 13 to direct the flow of electrons from the photocathode 13a to the anode 13c via the dynodes 13b. The voltage pulse which is derived from the pulse generator 16 may have a short duration of the order of one-hundredth of a microsecond, but the duration may not be shorter than the transit time of the electrons from the cathode to the anode of the tube.

The variable delay device 18 may be adjusted so that the tube 13 is conducting only during a short interval of time corresponding to the interval in which the incoming light intensity is to be observed. The tube conducting period should not exceed the time it takes to develop gas-generated noise in the tube 13, which varies with the voltage applied to the tube electrodes but which is usually about one microsecond. The output voltage from the photomultiplier tube 13 which is applied to the indicating device 21 through the integrating circuit 22, is substantially free from gas-generated and thermal noise.

Although a light source 10 controlled by the variable trigger rate generator 11 is illustrated in the drawing, it is understood that the photomultiplier tube circuit in accordance with this invention may be used to detect the intensity of any light which either originates within or without the circuit, whether it be constant, variable or pulsatory light, by proper adjustments in the variable trigger rate generator 11 and the variable delay device 18 to effect coincidence between the activation of the photomultiplier tube 13 and the desired aspect of the incident light.

FIG. 2 illustrates diagrammatically one form of a pulse generator which may be used to supply voltage pulses to the photomultiplier tube 13 shown in FIG. 1. This pulse generator comprises a conventional power supply 23 which is capable of providing direct voltages of, say, from 0 to 5,000 volts, a predetermined length of coaxial cable 24, a resistor 25 connected between the cable 24 and ground, a charging reactor 26 connected between the cable 24 and the power supply 23 and a gaseous triode tube 27 connected to ground and the cable 24 during conduction thereof. The voltage at the control grid of the gaseous triode tube 27 controls the repetition rate of the output voltage pulses developed across resistor 25. The duration of one of these pulses is determined by the length of the coaxial cable 24 which is charged by the voltage from the power supply 23 with the aid of charging reactor 26. The voltage from the power supply 23 is applied to cable 24 so that each time when the gaseous triode tube 27 discharges, the shield of the coaxial cable 24 becomes negative and a negative pulse is developed across the resistor 25. This negative pulse can then be transmitted to the electrodes of the photomultiplier tube 13 through coupling capacitor 17 to the voltage divider 14 shown in FIG. 1.

Referring now to FIG. 3, which is a more detailed diagram of another embodiment of a pulsed photomultiplier tube circuit in accordance with this invention, a variable frequency astable multivibrator 30 having a twin-triode tube 31 supplies a triggering voltage to the light source circuit 28 and to the light detector circuit 29, the operation of which is similar to the above-described operation of the circuit illustrated in FIG. 1 and therefore needs only a brief description.

Considering first the light source circuit 28, it is seen that the triggering voltage from the multivibrator 30 is applied to the control grid of the amplifier tube section 32. The amplified triggering voltage is then applied to the control grid of a cathode-follower amplifier tube section 33 in order to impedance match the integrating circuit

These principles have been previously used in light-beam ranging devices. However, an objectionable feature of this type of system is that the intensities of reflected light are usually very low and, hence, heretofore have been undetectable.

In a light-beam ranging system, a fast rising light pulse must be transmitted to the reflecting object to obtain satisfactory resolution. This light pulse may be derived satisfactorily from a known light source comprising a pulsed tube, for example, a thyratron, capable of producing a light pulse with a rise time of less than 0.1 microsecond, which may be even as low as 0.01 microsecond. If 0.01 microsecond pulses are used in a ranging device, the resolution is about plus or minus 1.5 meters.

In accordance with this invention, the reflected light is intercepted by a phototube which is pulsed on for approximately a 0.1 microsecond interval of time at a predetermined time after the light pulse has been transmitted to the reflecting object. The output of the pulsed phototube is fed to a sensitive current indicating device through an integrating circuit. The voltage pulses which pulse on the phototube are phased to produce the maximum current at the output of the phototube, i.e., a voltage pulse is applied to the phototube at a time interval corresponding to the time in which a reflected light pulse is received at the phototube. The time interval between the instant at which the light pulse is transmitted from the light source and the reflected pulse is received in the phototube, is a measure of the distance of the reflecting object, i.e.,

$$d = \frac{ct}{2}$$

where d is the distance, c is the velocity of light, and t is the time interval.

The light pulse and the phototube may be pulsed repetitively at rates up to at least 20,000 pulses per second. By using this pulse technique and current integration, it has been found that ten photoelectrons per second can be readily detected. This means that only one effective reflected photon out of every 2,000 pulses is required to detect the delay time of the reflected light-beam.

FIG. 5 illustrates a light-beam ranging system in accordance with this invention. The trigger rate generator 11 connected to the light pulse source 78 controls the transmitted light pulse repetition rate. The transmitted pulses 79 are intercepted by the photocathode 13a of photomultiplier tube 13 after they are reflected by an object 80.

The trigger rate generator 11 is also connected to the photomultiplier tube 13 through a variable delay device 18 and a serially connected adjustable pulse generator 16 in the manner described hereinbefore with reference to FIG. 1. The variable delay device 18 is adjusted to a position at which the reflected light pulses and the voltage pulses from the pulse generator 16 coincide in time at the photocathode 13a. The output of the photomultiplier tube 13 is then fed from the anode 13c to an integrating circuit 83, to which is connected an indicating device 84. The variable delay device 18 may be calibrated to give direct readings of distance between the photomultiplier tube 13 and the reflecting object 80.

In light-beam radar systems utilizing photomultiplier tubes operating on direct voltage, light from the light pulse source which is scattered by the atmosphere and objects in the immediate vicinity of the transmitter, produce a strong undesirable signal in the photomultiplier tube which tends to overload the tube for an interval of time immediately following the transmission of each light pulse. The recovery time of the photomultiplier tube after being overloaded is greater than the duration of the back-reflected light. A reflected light pulse received at the tube from the reflecting object during the recovery time is undetectable due to the large and noisy output of the photomultiplier tube caused by the back-scattered

light. Since in the present invention the photomultiplier tube is not pulsed on until the light pulse from the reflecting object is received, back-scattered light cannot overload the tube. Therefore, the present invention eliminates the need for an opaque partition between the light pulse source and the receiver, which is ordinarily necessary to minimize the effect of back-reflected light when operating a photomultiplier tube in a light-beam radar system on direct voltage.

5 Yet another embodiment of this invention relates to a receiver in a light-beam identification and/or signaling system.

In a military operation it is very often desirable to identify an object as friend or enemy. This can be accomplished by equipping all friendly objects with a light source that can be pulsed on in any preset series of pulses whenever a proper signal is received. This signal may be received from a radio or light-wave receiver that is tuned to a proper frequency for receiving a signal from a central interrogating transmitter.

15 At the interrogating transmitter, or in line of sight of the interrogated object, a light receiver is disposed to receive the light pulses from any object that is friendly. Enemy objects, not having the proper system equipment, 20 do not transmit the preset signal when interrogated and are thereby identified.

In accordance with this invention the light receiver includes a photomultiplier tube having operating voltage pulses applied thereto only during the time that a light 30 pulse is anticipated. Consequently, the sequence of the operating voltage pulses corresponds with the preset coded sequence of light pulses from the friendly light transmitter.

This system has the following advantages over a system using a detector which is continuously sensitive: 35 (1) great gain is obtained by pulse operation; (2) a predetermined code can be used, thereby providing greater security against enemy duplication; (3) the possibility of enemy jamming is almost completely eliminated; and (4) interference from other light flash sources, such as exploding shells, searchlights, etc., is eliminated. Furthermore, greater secrecy may be obtained by transmitting infra-red or ultra-violet light instead of ordinary artificial or natural light.

40 In FIG. 6 there is illustrated a light beam identification system in accordance with this invention. A synchronizing device 85, for example, a radio transmitter, either broadcast or directional, located preferably at station #1, which may be a central interrogating station, transmits a signal which is received in receiver 86 of station #2 at the 45 interrogated object. A pulse generator 87, connected to the output of receiver 86, produces voltage pulses when a signal is received by the receiver 86. The voltage pulses from the generator 87 are passed through a coder 88 and applied to the light pulse source 89 in a coded sequence. 50 A preset coded sequence of light pulses is then transmitted from the light pulse source 89 to station #1 wherein the light pulses are intercepted by the photocathode 13a of the photomultiplier tube 13.

The signal from the synchronizing device 85 is also 55 picked up by the receiver 90 at station #1 and applied to the pulse generator 91 which sends voltage pulses through a variable delay device 92 to coder 93. This coder 93 applies a preset coded sequence of operating voltage pulses, corresponding to the sequence of light pulses, to the photocathode 13a and dynodes 13b of the photomultiplier tube 13, which is constructed and operated as described hereinbefore with reference to FIG. 1. The variable delay device 92 is adjusted to a position at which the light pulse sequence and the voltage pulse sequence are in 60 phase at the photocathode 13a of the photomultiplier tube 13. It can be readily seen that the variable delay device 92 may be inserted in other parts of the system to produce the desired phasing between the light pulses and the voltage pulses. The identification of friend or foe may be 65 made, for example, by means of an indicating device 94

34, 35 which is connected across resistor 36. The rheostat 34, which is part of the integrating circuit 34, 35, is used as a continuous variable delay device for the positive voltage which is derived from the resistor 36. When the positive voltage across capacitor 35 of the integrating circuit 34, 35 reaches a predetermined value, the gaseous triode or thyratron 37 of the pulse shaper 55 is caused to fire. During the firing or conduction of the thyratron 37, a positive signal is taken from across resistor 38 to provide a positive pulse to operate the blocking oscillator 39, which includes the triode section 40. The output of the blocking oscillator 39 is taken from the tertiary winding 41 of the oscillator 39 and applied to the control grid of another cathode-follower amplifier tube section 42 which provides a low impedance trigger to the light-emitting hydrogen thyratron 43. The filter circuit 44 is inserted between the thyratron 43 and the blocking oscillator 39 to prevent transients from reflecting back to the blocking oscillator 39 when the thyratron 43 fires. The pulse-forming network 45 which is coupled to the thyratron 43, controls the duration of the light pulses emitted from thyratron 43. The anode voltage for the thyratron 43 is fed through the hold-off diode 46, which prevents inverse voltage from getting back into the power supply circuit, not shown, which is connected at point 47. The pulse-forming network 45 and the hold-off diode 46 and associated circuitry are conventionally used with thyratrons and, therefore, further explanation is deemed unnecessary.

Now, considering the light detector circuit 29, it is seen that the triggering voltage from the multivibrator 30 is also applied to the control grid of the amplifier tube section 48. The amplified triggering voltage is then applied to the control grid of a cathode-follower amplifier tube section 49 which provides a low impedance trigger through the step delay line 50 to the thyratron 51. The step delay line 50 may have a plurality of step positions, e.g., three step positions, as shown in FIG. 3. Position *a* may represent no delay; position *b* one microsecond delay; and position *c* two microseconds delay. The length of coaxial cable 52 determines the width of the output pulse from thyratron 51 in a manner which is well-known in the art. The positive pulse from thyratron 51 is then amplified in the amplifying tube 53 where it is inverted and applied as a negative pulse of high amplitude to the photomultiplier tube 13 through capacitor 54. The photomultiplier tube 13 and its output circuit, which includes the integrating circuit 22 and the electron microammeter 56, may be similar in design and operation to the photomultiplier tube and its output circuit illustrated in FIG. 1.

Although pulsed photomultiplier tubes are known in the art, this invention provides an improved photomultiplier tube circuit which can determine the intensity of light which has a lower intensity than any intensity heretofore detected and, furthermore, to determine the intensity of this light as a function of time.

From the foregoing description it can be seen that the present invention also provides an improved photomultiplier tube circuit in which the photomultiplier tube is substantially free from gas-generated and thermal noise even when operated at voltages having a magnitude many times that of its rated direct voltage.

Inasmuch as the invention makes it possible to detect light pulses of extremely small intensity values, it will be evident that the invention has particular utility in connection with communication systems making use of light pulses whose periodicity, amplitude, duration or phase position is modulated as a function of an intelligence or control signal.

Still another embodiment of this invention relates to a light-beam communication system which utilizes delta modulation principles.

Delta modulation is a pulse modulation system wherein pulses having a substantially constant amplitude are produced at the transmitting end at equidistant time intervals but wherein only selected pulses determined by the

nature of the modulating signal are transmitted. An example of a known delta modulation system wherein intelligence is conveyed via electrical pulses is fully described in the "Philips Research Reports," volume 7, pp. 442-466, December 1952, and "Philips Technical Review," volume 13, pp. 237-268, March 1952.

In accordance with the present invention, the delta modulated light pulses are radiated and intercepted to establish a communication link. In this light-beam system the receiver is a light-sensitive device, namely a photomultiplier tube, which produces an electrical pulse each time a transmitted light pulse is received. The detector is made sensitive to light only during the interval of time during which a light pulse is expected. At all other times, that is, in the interpulse time, the light-sensitive device is made inoperative and, therefore, noise cannot enter the system during this time.

The receiver in this communication system, which is illustrated in FIG. 4, is constructed and operated similarly to the circuit described in FIG. 1 and, therefore, only a brief description is deemed necessary.

FIG. 4 shows a transmitter 57 transmitting light pulses 58 to a receiver 59 which is synchronized with the transmitter by a signal from the synchronizing device 60 which may be, for example, a radio transmitter or a transmission line. The block diagram of transmitter 57 includes a pulse generator 61 which supplies a series of identical equidistant pulses 62 to the junction point 63 through a pulse modulator 64 with either unchanged or opposite polarity. The action of the pulse modulator 64 is governed by the polarity of the difference voltage obtained from the difference meter 65 by comparison of the modulating signal 66 and the step-like approximating signal 67 formed from the series of pulses 68 by integration in the integrating network 69. The suppressor 70 suppresses the negative pulses and passes the signal 71 to the light pulse source 72 which produces light pulses 58 corresponding to the electrical signal 71.

The light pulses 58 are intercepted by the photo-cathode 13a of the photomultiplier tube 13 in the receiver 59. The trigger rate generator 11, the variable delay device 18 and the adjustable pulse generator 16 are timed and adjusted to apply a pulse voltage to the photocathode 13a and dynodes 13b through the voltage divider 14 each time a light pulse is expected at the photocathode 13a. When the signal pulses at the anode of the tube 13 are applied to the integrating circuit 22, a signal 73 is produced thereacross which is a close approximation of the original signal 66. The signal appearing across the integrating circuit 22 is supplied to a utilizing device 76, for example, a loudspeaker, via a low-pass filter 74 and amplifier 75 suppressing inter alia the pulse recurrence frequency. Other suitable circuits, such as those described in the above-mentioned publications, may be coupled to the output of the tube to reproduce the original signal.

The advantages of this light-beam communication system are: (1) no gas-generated noise; (2) thermal noise is reduced by the factor

$$f = \frac{1}{P_w P_r}$$

where *f* is the reduction factor, *P_w* is the voltage pulse width, and *P_r* is the voltage pulse repetition rate; and (3) extremely high gain is possible.

An important advantage of this communication system over other types of light-beam systems is its ability to operate when the light signal received is so weak that only one photoelectron is emitted for each pulse received.

Other systems, e.g., amplitude modulation and pulse frequency modulation, require considerably higher light levels.

A still further embodiment of this invention relates to a light-beam ranging system for determining the distance to a reflecting object in accordance with radar principles.

such as an electron microammeter, which is connected to the output of the photomultiplier tube 13 through the integrating circuit 95.

It is to be understood that the above-described embodiments are illustrative of the application of the principles of this invention. Numerous other embodiments may be devised by those skilled in the art to which this invention pertains without departing from the scope thereof.

Having thus described my invention, what I claim and desire to secure by Letters Patent is:

1. In a light detector, the combination comprising a photomultiplier tube including a plurality of dynodes, said tube having the characteristic of producing gas-generated noise signals when voltages having relatively high values are applied to said dynodes for more than a relatively short period of time, resistance means connecting said dynodes to a point of reference potential to render said tube normally inoperative, a source of electrical pulses having a period of time shorter than the time in which said gas-generated noise is normally developed in said tube, and means connected to apply said pulses to said dynodes.

2. In a light detector, the combination comprising a photomultiplier tube including a plurality of dynodes and a cathode, said tube having predetermined operating voltage ratings for said dynodes and said cathode, said tube having the characteristic of producing gas-generated noise signals when voltages having relatively higher values than said voltage ratings are applied to said cathode and dynodes for more than a relatively short period of time, resistance means connecting said dynodes and cathode to a point of reference potential to bias said cathode and dynodes at a value to render said tube normally inoperative, means providing direct voltage operating pulses for said dynodes and said cathode having values substantially in excess of said voltage ratings for a period of time shorter than the time in which said gas-generated noise is developed in said tube, and means connected to apply said pulses to said dynodes and said cathode, respectively.

3. A light detector comprising a photomultiplier tube having electrodes including a photocathode, a plurality of dynodes and an anode, said tube having the characteristic of producing gas-generated noise signals when voltages having relatively high values are applied to said dynodes for more than a relatively short period of time, a plurality of series-connected resistors having one end connected to said photocathode, the other end connected to ground and the junctions therebetween connected respectively to said dynodes, an indicating device, an integrating circuit coupling said device to said anode, and a source of unidirectional pulse voltages having a predetermined low value and a predetermined high value coupled to the electrodes of said photomultiplier tube through said series-connected resistors for directing the flow of electrons from said photocathode via said dynodes to said anode, the duration of each of said unidirectional pulse voltages being less than the time in which said gas-generated noise is developed in said photomultiplier tube, said low value being of a magnitude producing substantially cut-off conditions in said tube.

4. A light detector, as set forth in claim 3, including voltage-determining means connected to control said values of pulse voltage whereby said predetermined low value is zero and said predetermined high value is substantially greater than the rated direct voltage for the electrodes of said photomultiplier tube, and including means connected to control the duration of said pulse voltages whereby the duration of each of said pulse voltages is not greater than one microsecond.

5. A light detector comprising a photomultiplier tube having a photocathode, a plurality of dynodes and an anode, said tube having the characteristic of producing gas-generated noise signals when voltages having relatively high values are applied to said dynodes for more than a relatively short period of time, a voltage divider

having a plurality of equally spaced taps connected between said photocathode and ground, said taps being respectively connected to said dynodes, said voltage divider being adapted to bias said cathode and dynodes at a value to render said tube normally inoperative, a current-sensitive device, an integrating circuit coupling said device to said anode, a pulse generator coupled to said photomultiplier tube through said voltage divider for applying to said photocathode and said dynodes voltage pulses having a magnitude substantially greater than the magnitude of the rated direct voltage of said photomultiplier tube for directing the flow of electrons from said photocathode to said anode, the duration of each of said pulse voltages being less than the time in which said gas-generated noise is developed and being not greater than one microsecond, and a variable trigger rate generator coupled to said pulse generator to control the pulse repetition rate thereof.

6. A light detection system comprising a photomultiplier tube having a photocathode, a plurality of dynodes and an anode, said tube having the characteristic of producing gas-generated noise signals when voltages having relatively high values are applied to said dynodes for more than a relatively short period of time, a plurality of series-connected resistors having one end connected to said photocathode, the other end connected to ground and the junctions therebetween connected respectively to said dynodes, the series resistor connection between said dynodes and cathode and ground providing a bias on said dynodes and cathode that renders said tube normally inoperative, an indicating device, an integrating circuit coupling said device to said anode, a pulse generator coupled to said series-connected resistors for applying to said photocathode and said dynodes voltage pulses having a magnitude many times the magnitude of the rated operative direct-current voltage of said photomultiplier tube, the duration of each of said pulse voltages being less than the time in which said gas-generated noise is developed and being not greater than one microsecond, a variable trigger rate generator coupled to said pulse generator to control the pulse repetition rate of the voltage pulses, a light source for producing pulsatory light and disposed to transmit said light to said photocathode, said variable trigger rate generator being coupled to said source to control the repetition rate of said pulsatory light, and a variable delay device interposed between said trigger rate and said pulse generators for phasing the voltage pulses from said pulse generator with respect to the light pulses from said light source.

7. A light detection system comprising a variable trigger rate generator producing voltage pulses, a first pulse amplifier coupled to the output of said generator, a first pulse shaper, a continuous variable delay device coupling said amplifier to said shaper, a blocking oscillator coupled to the output of said shaper, a light source comprising a gas discharge tube, a filter circuit coupling the output of said blocking oscillator to said light source for preventing transients from reflecting back to said blocking oscillator, a second pulse amplifier coupled to the output of said variable trigger rate generator, a second pulse shaper providing shaped pulses each of which has a duration less than one microsecond, a step delay device coupling said second amplifier to said second shaper, a photomultiplier tube having a photocathode, an anode and a plurality of dynodes, said tube having the characteristic of producing gas-generated noise signals when voltages having relatively high values are applied to said dynodes for more than a relatively short period of time, said photocathode being disposed to receive light from said light source, a plurality of series-connected resistors having one end connected to said photocathode, the other end connected to ground and the junctions therebetween connected respectively to said dynodes, the series resistor connection between said photocathode, dynodes and ground providing a bias on said dynodes that renders

11

said tube normally inoperative, a third pulse amplifier amplifying and applying said shaped pulses with a negative polarity to said photocathode and through said resistor to said dynodes to render said tube operative in a pulsatory manner, said shaped pulses having durations less than the time in which said gas-generated noise is developed, a current-sensitive device, and an integrating circuit coupling said current-sensitive device to said anode. 5
